WINDOW MEMBER EXTRUSION

Richard N. Anderson, Owensboro, Ky., assignor to V. E. Anderson Mfg. Co., Owensboro, Ky., a corporation of Kentucky

Filed Oct. 16, 1967, Ser. No. 9,129

Term of patent 14 years

(Cl. D13—6)

FIGURE 1 is a perspective view of a window member extrusion particularly showing the front, one side and one end of my new design.

FIGURE 2 is a perspective view of the window member extrusion particularly showing the back, other side and other end thereof.

FIGURE 3 is an enlarged transverse section view of the window member extrusion.

I claim:

The ornamental design for a window member extrusion, substantially as shown and described.
